[57] CLAIM

The ornamental design for metered package blank,
substantially as shown and described.

DESCRIPTION

FIG. 1 is a top plan view of a metered package blank
showing my new design; and

FIG. 2 is a bottom plan view thereof;

FIG. 3 is a left side elevational view thereof;

FIG. 4 is a right side elevational view thereof;

FIG. 5 is a rear elevational view thereof;

FIG. 6 is a front elevational view thereof.
